UNITED STATES PATENT OFFICE.

JACOB H. FLEISCH, OF NEW YORK, N. Y.

DESIGN FOR A COMBINATION-GARMENT.

SPECIFICATION forming part of Design No. 29,425, dated September 27, 1898.

Application filed August 30, 1898. Serial No. 689,872. Term of patent 7 years.

To all whom it may concern:

Be it known that I, JACOB H. FLEISCH, a citizen of the United States, residing in the city of New York, borough of Manhattan, in the county of New York and State of New York, have invented and produced a new and original Design for a Combination-Garment, of which the following is a specification, reference being had to the accompanying drawings, forming a part thereof.

Figure 1 is a front view of a garment, showing my design; and Fig. 2 is a section on the line 2 2 of Fig. 1.

As shown in the accompanying drawings, the leading or material feature of my design consists of the front flaps 1 on the body 2, the edges of which are curved from top to bot-

tom. Connecting the flaps at the top is a collar 3, and at the junction of the collar ends and the flaps are V-shaped notches. Connected to the flaps 1 and extended inward therefrom are vest-like flaps 4, which are narrower at the upper end than at the bottom. At the top of each vest-like flap and extended partly around the collar-band is a triangular flap 5.

I claim—

The design for a combination-garment, as herein shown and described.

J. H. FLEISCH.

Witnesses:

NATHAN FLEISCH,
SAMUEL FLEISCH.
